INVENTOR.

TIMOTHY F. HORAN

BY

Thomas L. Wilder

ATTORNEY.

UNITED STATES PATENT OFFICE.

TIMOTHY F. HORAN, OF ILION, NEW YORK.

FIREARM.

Application filed August 27, 1918. Serial No. 251,697.

To all whom it may concern:

Be it known that I, TIMOTHY F. HORAN, a citizen of the United States, residing at Ilion, in the county of Herkimer and State 5 of New York, have invented certain new and useful Improvements in Firearms, of which the following is a specification, reference being had therein to the accompanying drawing.

10 My invention relates to an automatic firearm and I declare the following to be a full, clear, concise and exact description thereof sufficient to enable anyone skilled in the art to which it appertains to make and use the 15 same, reference being had to the accompanying drawings in which like reference characters refer to like parts.

The object of the invention is to provide a gas operated firearm that will act automatically. The firearm is of simple construction embodying an actuator, a breech block, a trigger, a main spring and a trigger spring. The firearm is equipped also with a 25 breech bolt which is adapted to effect a semiautomatic operation of the gun. The sear is controlled by a sliding bar which can be manipulated to convert the firearm from an automatic to a semiautomatic gun as well as to act as a safety lock.

30 The features will be understood by referring to the drawings in which:

Fig. 1 is a fragmentary view showing a vertical section of the firearm with certain parts in elevation;

35 Fig. 2 is a transverse section taken on the line 2—2 of Fig. 1;

Fig. 3 is a fragmentary view, showing a vertical longitudinal section of the receiver portion of the firearm and certain relative 40 parts in elevation;

Fig. 4 is a fragmentary side view, on a reduced scale, of the firearm;

Fig. 5 is a fragmentary view of the actuator of the firearm, showing a modified form 45 of breech bolt in vertical section;

Fig. 6 is a vertical section of a still further modified form of breech bolt, used in connection with the firearm;

Fig. 7 is a fragmentary perspective view 50 of an actuator employed in connection with the modified form of breech bolt shown in Fig. 6;

Fig. 8 is a vertical section on a reduced scale of the firearm, taken on the line 8—8 55 of Fig. 3;

Fig. 9 is an end elevation of a cartridge magazine;

Fig. 10 is a plan view of the sear;

Fig. 11 is a side elevation of the sear shown assembled with the trigger; 60

Fig. 12 is a perspective view of the actuator and firing pin of the firearm;

Fig. 13 is a perspective view of the breech bolt;

Fig. 14 is a perspective view of the sear 65 of the firearm;

Fig. 15 is a perspective view of a sliding safety bar;

Fig. 16 is a transverse section on a reduced scale taken on the line 16—16 of Fig. 3, 70 looking in the direction indicated by the arrows;

Fig. 17 is a transverse section taken on the line 17—17 of Fig. 4;

Fig. 18 is a transverse section taken on the 75 line 18—18 of Fig. 4;

Fig. 19 is a perspective detail view of a spring used in connection with the cartridge magazine;

Fig. 20 is a transverse horizontal section, 80 looking down from above, upon the line 20—20 of Fig. 13.

Referring more particularly to the drawings, the firearm has a barrel —1— with the usual rifling for giving the bullet a twirl, as 85 it is projected from the barrel. The barrel —1— is equipped with ribs A for cooling purposes and the threads 2, whereby it is secured to the correspondingly threaded aperture of the receiver 3. The receiver 3 is 90 shouldered at 4 for the reception of the shouldered end of the metal piece 5. The stock 6 is attached to the metal piece 5 by a bolt 7. The head of bolt 7 rests in a metal socket-piece 7^a. The metal piece 5 is attached also to the receiver 3 by a bolt 8 that 95 engages a threaded aperture in the forward part of the metal piece 5. The bolt 8 is hollow and adapted for the reception of the bolt 9 which is threaded at its upper end to the 100 receiver 3. By removing the bolts 8 and 9, the receiver 3 and metal piece 5 can be dissociated.

A collar 11 is mounted upon the forward part of the barrel —1— and is provided with 105 a depending hollow cylinder 12 for the reception of the forward end of the gas tube 13. A screw 14 with a tapered upper end and having a conduit 15 and a passageway 16 at right angles thereto passes up through 110

a threaded orifice in the cylinder 12, whereby to form a conduit from the bore of the barrel —1— to the interior of the gas tube 13. The gas tube 13 is located just below the 5 barrel —1— and is supported at its rear end by the collar 18 that partly surrounds the barrel —1—. The collar 18 also holds the forward part of the forestock 19. The rear end of the forestock 19 is held by the bolt 8.

10 The rear end of the gas tube 13 is open at 20.

The gas tube 13 contains the hollow piston 21 of the actuator. The rear part of the actuator is bifurcated at 21 forming the oppositely disposed flat bars 22—22. The flat 15 bars 22 are reduced to form recesses 23—23 with inclined surfaces at 24—24. An irregular shaped piece 25 is attached to the free ends of the bars 22. The piece 25 has an upwardly extending part 26 from which projects forwardly the firing pin 27 that is made 20 integral with the part 26. The piece 25 has also the lateral projecting lugs 28—28 which slide in corresponding guide grooves 29—29 formed in the sides of the receiver 3. The 25 rear ends of the guide grooves 29 are open at 30 to permit the dissociation of the actuator.

A coiled spring 31 is disposed within the chamber of the hollow piston 21 and bears at 30 one end against the forward inner surface of the piston 21 and at the other end against the part 32^a of the receiver 3 which part extends down between the flat bars 22. The coiled spring 31 normally pushes the actuator 35 forward.

The inverted U-shaped breech block 32 is disposed over the firing pin 27 and over the irregular shaped piece 25 attached to the rear ends of the bars 22. The breech block 40 32 is open at its base and has a closure at 33 provided with an aperture 35 for the forward end of the firing pin 27. The front surface of the closure 33 is adapted for pushing the cartridges 36 into the barrel —1—.

45 Lugs 37—37 formed integral with the rear end of the breech block 32 project downwardly and forwardly and are adapted to fit loosely into the correspondingly formed recesses 23—23 of the bars 22—22, so as to 50 move freely in and out of said recesses 23. The pitch or angle of the lugs 37 is slightly more near to the vertical than the angle of the recesses 23, whereby to aid in forcing the lugs 37 out of the recesses 23. The lower 55 edges 40—40 of the inverted U-shaped breech block 32 are tapered at 41—41 to fit over the taper 42 of the bars 22 of the actuator. Said edges are tapered less from 42^a to the front end 43 of the breech block 32, 60 whereby to allow a little space between said edges and the upper edges of the flat bars 22. This space will permit the movement of the breech block 32 independent of the actuator, whereby the rear end of the breech block 32 can move up into the shouldered 65

recess 44 illustrated in Fig. 3. The forward end of the breech block 32 is equipped with the overhanging jaws 45—45 to form a guide groove 46 for the passage of the rims 47 of the cartridges 36. The groove 46 is formed 70 on the arc of a circle, so as to direct the cartridges 36 toward the lateral opening 48 in the receiver 3. A shoulder 50 inside the breech block 32 forms a stop against which the adjacent part 26 of the piece 25 of the 75 actuator abuts, whereby to arrest the forward movement of the actuator under the influence of the coiled spring 31.

The firing pin 27 is held in cocked position by the trigger 52 having a shoulder at 53 for 80 the purpose. The trigger 52 is fulcrumed upon a pivot pin 54 which is mounted in the sides of the receiver 3. The shoulder 53 is held up normally in the path of the forward edge of the irregular shaped piece 25 85 between the bars 22 by a coiled spring 55 that is partly housed in a recess formed in the metal piece 5. The free end of the trigger projects through a recess 56 made in the metal piece 5, which recess allows the necessary rotation of the trigger 52 upon its pivot pin 54. The metal piece 5 is recessed at 57 and is formed with the usual guard 58 for the free end of the trigger 52.

In order to make the firearm semiautomatic, or in other words to load the gun automatically and to fire each time the trigger 52 is pulled, there is employed a sear 60 which is fulcrumed upon the same pivot 54 that supports the trigger 52. The sear 100 60 has one long arm 61 and a shorter arm 62 which arms straddle the upper end of the trigger 52. The rear end of the sear 60 is raised normally by a coiled spring 64 that has one end disposed in a suitable recess made in the trigger 52 and the other end disposed against the projecting lug 65 formed on the sear 60. This elevation of the rear end of the sear 60 will hold the shoulder 66 formed on the sear 60 in the 110 path of the shoulder 67 provided on the base of the irregular shaped piece 25 of the actuator. The engagement of the shoulder 66 on the sear 60 with the shoulder 67 on the piece 25 will stop the forward movement of the actuator under the tension of the spring 31 and hold the same just before it comes to cocked position or just before the shoulder 67 on the piece 25 has come into engagement with the shoulder 53 120 of the trigger 52.

The projecting lug 65 of the sear 60 fits into a slot 68 formed in the trigger 52, whereby to limit the upward movement of the rear end of the sear 60 under tension 125 of the spring 64 and also to effect, at the proper time, a depression of the rear end of the sear 60 when the trigger pull is released and the trigger 52 turns upon its fulcrum pin 54 to normal position illus- 130

trated in Fig. 3. This depression of the rear end of the sear 60 will disengage the shoulder 66 thereof from the shoulder 67 on the base of the piece 25, whereby to permit the actuator to travel forward a very small fraction of an inch until it is stopped in cocked position by the shoulder 53 of the trigger 52.

The mechanism for controlling the automatic and semiautomatic action of the firearm embodies a sliding bolt 70 which is mounted in the metal piece 5. The lower surface of the bolt 70 is recessed at 71 and has three notches 72, 73, and 74 countersunk 15 in said recess 71 in which notches plays the upper surface of the spring pressed plunger 75, whereby to limit the movement of the bolt 70 and to hold the same temporarily in any one of three positions. The recess 71 prevents the displacement of the bar 70 from the gun. The upper surface of the bolt 70, or that opposite the recess 71, has two notches 76 and 77, the notch 77 being larger than 76, and a shoulder 78 disposed 25 between the notches 76 and 77. When the plunger 75 rests in the middle notch 73 of the three notches or when the ends of the bolt 70 are substantially flush with the outer surfaces of the metal piece 5, the shoulder 78 of said bolt 70 will lie immediately below the forward end 53 of the trigger 52 and thereby prevent the turning of the trigger 52 upon its fulcrum pin 54. This disposition of the bolt 70 will provide 30 a safety lock to prevent the firing of the gun. When the bolt 70 is pushed to the right as shown by dotted lines in Fig. 8, the shoulder 78 will clear the forward end 53 of the trigger 52 and lie below the forward end 40 of the long arm 61 of the sear 60, thereby holding the shoulder 66 of the sear 60 down, so that it will clear the shoulder 67 on the irregular shaped piece 25. At the same time, the notch 76 will lie under 45 the forward end 53 of the trigger 52 and permit its free movement upon its fulcrum pin 54. This disposition of the bolt 70 will lock the sear and, thereby permit the gun to shoot automatically, so long as the trigger 52 is depressed. When, however, the bolt 70 is pushed to the left, the notch 77 will lie beneath the forward end of the trigger 52 and the arm 61 of the sear 60, thereby allowing the full operation of the sear 50 and of the trigger 52. This disposition of the bolt 70 will effect a semiautomatic firing of the gun, or the firing of the gun each time the trigger 52 is pulled. The arm 62 is made shorter than arm 61, so as 55 not to be affected by the movements of bolt 70.

The magazine 80 is a long narrow casing adapted for holding cartridges 36 and is equipped with a spring pressed follower 55 81, whereby the cartridges 36 are fed auto-

matically upward into loading position. The magazine 80 is held in a recess 83 formed in the metal piece 5 by a spring clip 84 attached to the casing at 85. The spring clip 84 has the shoulders 86—86 70 adapted to rest in correspondingly shaped recesses formed in the adjacent portion of the metal piece 5, when the spring clip 84 is in normal extended position. Guide members 87—87 having shoulders 88—88 75 are attached to the casing of the magazine and are adapted to slide in suitable grooves formed in the piece 5. The shoulders 88 limit the upward movement of the magazine 80. The upper portion of the magazine 80 occupies a space between the bars 22—22 of the actuator.

The operation of the firearm is effected by first disposing a loaded magazine 80 into place. Immediately the magazine 80 85 is pushed home in the receiver part 3 of the firearm, the spring clip 84 will automatically carry the shoulders 86 thereof into the recesses formed in the metal piece 5 to hold the magazine 80 in assembled position. When the magazine becomes empty, the same can be replaced by pressing forward with the finger on the lower end of the spring clip 84 and then pulling downward.

Assume the bar 70 is pushed to the right in which position the plunger 75 will engage the aperture 72 and, permit the automatic firing of the gun. The firing pin 27 and breech block 32 can be drawn back manually into cocked position by pulling on the handle 90 which projects through a slot 91 in the receiver 3 and is attached to one of the bars 22 of the actuator. When the actuator and firing pin has been drawn back, a cartridge 36 will rise automatically into loading position in front of the breech bolt 32 and the rim 47 of the cartridge will enter the grooves formed by the jaws 45 of the bolt. In this position of said parts, 100 the breech bolt 32 will push the cartridge forward into the chamber in the barrel —1—, immediately the handle 90 is released. This forward movement of the breech bolt 32 will be arrested by the engagement of the shoulder 67 of the irregular shaped piece 25 with the shoulder 66 on the sear 60. If the trigger 52 is pulled now and held, the actuator will move a short distance forward under the tension of the spring 31, independent of the breech bolt 32, thereby causing the lugs 37 on the rear end of the breech bolt 32 to ride up out of the recesses 23 of the bars 22 and force the rear top edge of the breech 115 bolt 32 temporarily into engagement with the shouldered recess 44 to temporarily lock the bolt 32. At the same time, the firing pin 27 which moves forward with the actuator will strike the primer of the 120 cartridge 36.

The magazine 80 is a long narrow casing adapted for holding cartridges 36 and is equipped with a spring pressed follower 55 81, whereby the cartridges 36 are fed auto-

cartridge 36 and explode the same. Immediately the explosion occurs, and the bullet is projected through the barrel —1—, the gases will expand through the conduit 15 5 and passageway 16 of the screw 14 into the gas tube 13 and force back the piston 21. When the lugs 37 come opposite the recesses 23 in the bars 22 which move backward with the piston 21, the same will drop 10 down therein, thereby unlocking the breech bolt 32 and causing it to move backward in unison with the actuator. The jaws 45 of the breech bolt will extract the empty shell from its chamber in the barrel —1—, 15 which shell will be ultimately ejected through the lateral opening 48. When the actuator reaches its rearmost position, the next cartridge 36 will spring into loading position, thereby pushing the empty shell 20 through the opening 48. The same operations just described, will be repeated, until all the cartridges 36 in the magazine 80 have been fired.

The gas tube 13 can be removed easily 25 by withdrawing screw 14 and then moving the collar 11 longitudinally towards the muzzle of the gun, whereby to release the rear end of the gas tube 13 from its seat in collar 18. The removal feature of the gas 30 tube 13 and screw 14 is convenient for cleaning said parts.

Fig. 5 shows a modification of the breech bolt, here referred to as 100. The breech bolt 100 carries the firing pin 101 which is 35 housed in a suitable recess in the breech bolt 100. The front end of the firing pin is reduced in diameter and surrounded by a coiled spring 102, which tends to press the firing pin towards the rear of the bolt 100. 40 The firing pin 101 is held against the tension of the spring 102, however, by a pin 103 that projects transversely through the elongated slot 104 formed in the firing pin 101. The pin 103 is mounted in the adjacent 45 sides of the breech bolt 100. The elongated slot 104 permits a given amount of longitudinal movement of the firing pin 101. In this construction, the firing pin 101 travels independent of the movement of 50 the actuator 107. The part 108 of the actuator 107 serves as a hammer, whereby to hit the firing pin 101, after the breech bolt 100 has been locked, as in the former construction, heretofore described.

55 Figs. 6 and 7 show a still further modification of the breech bolt 110 and the actuator 111. Here the firing pin 112 is housed in a recess formed in the breech bolt 110. The firing pin 112 is urged normally 60 forward by a spring 113 that bears at one end against the shoulder 114 formed by the head of the firing pin and at the other end against the collar 115 held to the breech bolt 110. The shaft of the firing pin 112 65 slides freely through the aperture of the

collar 115. The free end of the firing pin 112 is provided with a depending arm 116 that projects downwardly into a recess 117 formed by the walls 118 that unite the ends of the bars 119—119 of the actuator 111. 70

As in the former constructions, when the actuator 111 goes forward, it will carry the breech bolt 110 therewith and cause the rear end of the same to move up into locked position. Simultaneously with this 75 locked position of the breech bolt 110, the depending arm 116 connected to the firing pin 112 will be released by the shoulder 53 of the trigger 52. In the meantime, the actuator 111 has moved forward a short distance, independent of the firing pin 112, to allow the firing pin to move forward to explode the cartridge. After the discharge 80 of the cartridge, the opposite wall 118 of the actuator 111 will make contact with the depending arm 116 and thereby carry the breech bolt 110 and connected parts backward, preparatory to reloading the gun.

Having thus described my invention, 90 what I claim as new and desire to secure by Letters Patent is:

1. In a firearm, a barrel, a removable gas chamber, a screw having a tapered upper end, whereby to aid in holding said gas 95 chamber to said barrel, an actuator carrying a firing pin, a breech bolt, gas actuated means for moving said actuator, whereby to operate the breech bolt to reload the gun, and inclined surfaces on said actuator adapted to elevate one end of said breech bolt 100 into locked position for firing the gun.

2. In a firearm, a barrel, a gas chamber, a collar, a screw having a tapered upper end, whereby to aid in holding said collar 105 and gas chamber to said barrel, an actuator carrying a firing pin, a breech bolt having grooves for extracting the cartridges from the barrel, and bars having open inclined recesses, whereby to move said breech 110 bolt into locked position while firing the gun.

3. In a firearm, a barrel, a gas chamber, a hollow screw to aid in holding said gas chamber to the barrel, an actuator having 115 a firing pin attached, a breech bolt, grooves formed on the arc of a circle in the front surface of said breech bolt, whereby to extract the cartridges from the barrel, bars having recesses, and depending lugs on said 120 breech bolt adapted to slide in and out of said recesses, whereby to lock the breech bolt in firing position.

4. In a firearm, a barrel, a removable gas chamber connected with said barrel, a hollow screw having a tapered upper end, whereby to aid in holding the gas chamber to the barrel, a piston in said gas chamber, bars connected with said piston, open recesses in said bars, a breech bolt, and de 125 130

pending lugs on said breech bolt, adapted to ride in and out of said recesses, whereby to lock and unlock said breech bolt in firing position.

5 5. In a firearm, a barrel, a gas chamber, a piston in said gas chamber, a firing pin connected to move with the piston, a trigger, a sear having arms disposed on either side of the upper part of the trigger, and a

10 bolt having recesses and a shoulder adapted to co-operate with the arms of said sear and with the upper part of said trigger, whereby to effect a safety lock, an automatic firing of the gun or a semi-automatic 15 firing as desired.

6. In a firearm, a barrel, a gas chamber, a piston in said gas chamber, a firing pin connected to move with the piston, a trigger, a sear having arms disposed on either 20 side of the upper part of the trigger, a bolt having recesses and a shoulder adapted to co-operate with the arms of said sear and with the upper part of said trigger, whereby to effect a safety lock, an automatic firing 25 of the gun or a semi-automatic firing as desired, and a spring pressed plunger for holding said bolt temporarily in any one of three positions.

7. In a firearm, a barrel, a gas chamber, 30 a piston in said gas chamber, a firing pin, a trigger, a sear having arms of unequal length disposed on either side of the upper part of the trigger, a bolt adapted to move transversely, recesses and a shoulder formed 35 on said bolt, whereby to co-operate with the arms of said sear and with the upper part of the trigger to effect a safety lock, an automatic firing or a semi-automatic firing of the gun, as desired, and a spring pressed 40 plunger for holding said bolt temporarily in any one of three positions.

8. In a firearm, a barrel, a gas chamber, 45 a piston in said gas chamber, a firing pin, a trigger, a sear having arms of unequal length disposed on either side of the upper part of the trigger, a bolt adapted to move transversely, recesses and a shoulder formed 50 on said bolt, whereby to co-operate with the arms of said sear and with the upper part

of the trigger to effect a safety lock, an 50 automatic firing or a semi-automatic firing control of the gun, a spring pressed plunger for holding said bolt temporarily in any one of the three positions, and a lug formed on 55 said sear and adapted to fit into a slot formed in said trigger, whereby to limit the upward movement of the rear end of said sear.

9. In a firearm, a barrel, a gas chamber, a piston in said gas chamber, a firing pin, 60 a trigger, a sear having arms disposed on either side of the upper part of the trigger, a bolt adapted to move transversely, recesses and a shoulder formed on said bolt, whereby to co-operate with the arms of said sear 65 and with the upper part of the trigger to effect a safety lock, an automatic firing or a semi-automatic firing of the gun, as desired, a spring pressed plunger for holding said bolt temporarily in any one of the three 70 positions, and a shoulder on said sear for arresting the forward movement of the firing pin:

10. In a firearm, a barrel, a gas chamber, an actuator having a firing pin attached, a 75 breech bolt, grooves formed in the front surface of said breech bolt, whereby to extract the cartridges from the barrel, the upper end of said grooves being formed on the arc of a circle, whereby to eject the 80 cartridge shells from the firearm, and means for locking said breech bolt temporarily in firing position.

11. In a firearm, a barrel, a removable gas chamber, a hollow screw adapted to connect the gas chamber to the barrel, a piston in said gas chamber, a firing pin connected to move with the piston, a trigger, a sear having arms disposed on either side of the upper part of the trigger, and a bar adapted 85 to co-operate with said sear and trigger, whereby to effect a safety lock, an automatic firing of the gun, or a semi-automatic 90 firing as desired.

In testimony whereof I have affixed my 95 signature.

TIMOTHY F. HORAN.
